G. R. SHEPHERD.

OIL CAN NOZZLE.

APPLICATION FILED MAR. 17, 1919.

1,318,810.

Patented Oct. 14, 1919.

INVENTOR:

Geo. R. Shepherd
Knight Brown & May

ATTYS.

UNITED STATES PATENT OFFICE.

GEORGE R. SHEPHERD, OF BROOKLINE, MASSACHUSETTS.

OIL-CAN NOZZLE.

1,318,810.

Specification of Letters Patent.

Patented Oct. 14, 1919.

Application filed March 17, 1919. Serial No. 283,176.

To all whom it may concern:

Be it known that I, GEORGE R. SHEPHERD, a citizen of the United States, residing at Brookline, in the county of Norfolk and 5 State of Massachusetts, have invented new and useful Improvements in Oil-Can Nozzles, of which the following is a specification.

This invention relates to an oil can nozzle 10 adapted at its pouring end to displace the spring-closed cover of an oil cup, and pour oil into the cup without the necessity of contact of the operator's fingers with the oil cup and cover.

15 The object of the invention is to provide an oil can nozzle with improved cover-displacing means adapted to be conveniently located by the operator on the periphery of an oil cup, in suitable relation to the cover, 20 and to be conveniently manipulated to displace the cover and permit the nozzle to assume a suitable pouring angle, said means being embodied in an enlargement at the pouring end of the nozzle, made from a 25 single blank of sheet metal which may be either soldered to the body of the nozzle, or formed as an integral part thereof.

Of the accompanying drawings forming a part of this specification,—

30 Figures 1 and 2 are views of opposite sides of a nozzle embodying the invention.

Fig. 3 is an end view looking toward the pouring end of the nozzle.

Fig. 4 is a side view of an oil cup, illustrating a part of the operation of applying the nozzle to the cup and displacing the cover.

40 Fig. 5 is a longitudinal section of the cup and nozzle, showing the cover completely displaced and the nozzle in pouring position.

Fig. 6 is a side view of the blank from which the nozzle enlargement shown by the preceding figures is or may be made.

45 Fig. 7 is a perspective view of an alternative construction, the nozzle enlargement being integral with the body of the nozzle.

Fig. 8 is a longitudinal section of the nozzle formed as shown by Fig. 7.

50 Fig. 9 is a section on line 9—9 of Fig. 8. The same reference characters indicate the same parts in all of the figures.

An oil can nozzle embodying my invention is provided with an enlargement at its pouring end, said enlargement being provided with a substantially flat side portion 55 12 which is under the bore 13 of the nozzle

when the latter is in pouring position, a recess or notch 14 in one end of the side portion 12, adapted to receive a portion of the periphery of an oil cup 15, and an end portion 16, which is inclined relatively to the flat side portion 12 and the bore 13, and extends across the pouring end of the nozzle.

When the invention is embodied as shown by Figs. 1 to 5, inclusive, the enlargement is 65 formed from a single blank of sheet metal, formed as shown by Fig. 6. Said blank includes the wings 17, 17, adapted to be bent to form a tube or ferrule 18 embracing the nozzle body 19, and secured to the latter by 70 soldering or brazing, said wings having edges 17^a, which may abut together to form a joint at one side of the ferrule, as indicated by Fig. 2. The blank includes also the main portion 20, one end of which is 75 provided with the notches or recesses 14^a, 14^a, and the intermediate notch or recess 16^a. The body portion 20 is folded on itself 80 along the dotted lines 23, 23, (Fig. 6), to define the longitudinal edges of the flat side portion 12, the notches 14^a being thus brought into registration with each other to form the recess 14. The central portion 85 of the blank body containing the central notch 16^a is pressed to form a bridge 24, extending across one side of the nozzle body 19, as shown by Fig. 3. The pressing operation which forms the bridge 24, converts the wall of the notch 16^a into the inclined 90 end portion 16.

The flat side portion 12 and the end portion 16 meet to form the opposite sides of a wedge, the apex portion of which contains the recess 14.

95 A nozzle provided with an enlargement characterized as above stated, is adapted to be first placed against one side of the periphery of an oil cup 15, under the overhanging margin of the spring-closed cover 15^a of the cup, in the position shown by full 100 lines in Fig. 4, the inclined end portion 16 being in contact with the under side of the cover. The operator may now move the nozzle endwise while holding it in an inclined position, thus causing the side portion 12 to slide on the mouth of the cup to the position shown by dotted lines in Fig. 4, the end portion 16 at the same time sliding under and partially displacing the cup. The operator may now incline the nozzle to 105 pouring position, as shown by Fig. 5, this operation increasing the displacement of the 110

cover 15^a. The recess 14 is in the path of oil issuing from the nozzle so that oil flows through said recess into the cup, as indicated by the arrow in Fig. 5.

5 It will be seen that the operator is materially aided by the recess 14 in locating the nozzle enlargement on the periphery of the oil cup under the overhanging edge of the cover, and that after locating the enlargement, it is only necessary to tip the nozzle to a pouring angle shown by Fig. 5.

10 While I have described somewhat minutely the form of the blank from which the enlargement is made, I am not limited to 15 this particular form, it being obvious that an enlargement adapted to operate as described, may be made from a blank differently formed.

15 Figs. 7, 8 and 9 illustrate a nozzle enlargement embodying the invention, formed integral with the body of the nozzle, the blank in which the nozzle and enlargement is formed being folded upon itself at 25, to 20 define the longitudinal edges of the flat side portion 26, said blank being pressed to form conduit wall portions 27 constituting continuations of the bore of the nozzle, the blank being provided with ears 28 which are 25 abutted together and united by soldering or

brazing, said ears and the portions 27 being provided with inclined edges which collectively form the inclined end portion 29. One end of the enlargement formed as described is provided with a recess 30, adapted to receive a portion of the periphery of the oil cup, and having the same functions as the recess 14 above described. The portion of the nozzle enlargement containing the recess 30 projects forward from the pouring end of the nozzle, and is adapted to be inserted between the oil cup and its cover before the inclined end portion 29 comes to a bearing on the edge of the cover.

I claim:

An oil can nozzle having an enlargement 4 at its pouring end, said enlargement being provided with a substantially flat side portion which is below the bore of the nozzle, when the latter is in pouring position, a recess in one end of said side portion adapted 5 to receive a portion of the periphery of an oil cup, and a cover-lifting end portion which is inclined relatively to the said side portion, and extends across the pouring end of the nozzle.

In testimony whereof I have affixed my signature.

GEORGE R. SHEPHERD.
